REGENERATIVE STEAM POWER PLANT IN WHICH AN EXTRACTION TURBINE SUPPLIES STEAM TO DESUPERHEATERS WHICH SERVE TO HEAT FEED WATER

Richard C. Powell, Oakland, Calif.

Application March 2, 1949, Serial No. 79,259

5 Claims. (Cl. 60—67)

1

This invention relates to so-called regenerative cycles, used in turbine steam plants, and in which steam tapped from turbine stages is passed through feed water heaters.

As to those taps which supply superheated steam it is known practice to carry out the heat exchange with the feed water in two phases, in the first of which the superheat is extracted from the steam, and in the second the heat is extracted from saturated (or substantially saturated) steam. As so carried out the feed water received heat alternately from a desuperheater and a saturated steam heater, and where there were several taps the heat exchange was not particularly good because the temperature differences were not highly favorable.

According to the present invention, when there are several taps which deliver superheated steam, the steam of all is desuperheated in a desuperheater or desuperheaters in which the heat exchange is with feed water which has already passed through the saturated steam heaters. Where several desuperheaters are used their water paths may be connected in parallel or in series, and where a series arrangement is used it is preferred that the last superheater in the series receives the hottest steam.

By the above procedures an improved heat recovery is afforded without greatly complicating the circuit.

The precise nature of the exchangers is not material, and since the invention resides in the circuit the exchangers will be indicated diagrammatically according to an established Patent Office convention. Nothing is thereby implied as to the form of the heat exchangers, and the circuit can be laid out so simply as to be readily comprehended.

In the drawing:

Fig. 1 is a diagram of a circuit according to the invention, in which the water paths of the desuperheaters are in multiple.

Fig. 2 is a diagram of a circuit which is identical with Fig. 1 except that said water paths are in series.

Fig. 3 is a diagram of a system according to Fig. 1 elaborated by the use of secondary desuperheaters so that desuperheating occurs in more than one step. The first desuperheating step for all taps which supply superheated steam is effected in desuperheaters connected according to the invention.

Refer first to Fig. 1. The steam generator or boiler is indicated at 5 and supplies steam through line 6 to turbine 7 which drives electric generator 8, and exhausts from its last stage into

2

condenser 9. A feed pump 11 draws condensate from the hot well of the condenser and returns it to the generator 5 through the regenerative system which involves the present invention.

5 The parts 5 to 11 are understood to be conventional and are conventionally arranged.

Four taps T1, T2, T3 and T4 withdraw steam from stages of turbine 7. The first three are assumed to deliver superheated steam whereas T4 delivers steam which is saturated or substantially so.

The Patent Office convention for a heat exchanger is a shell with inlet and outlet connections, the shell enclosing a coil which also has inlet and outlet connections. On a purely arbitrary basis the desuperheaters and saturated steam heaters are here consistently drawn as if the feed water passed through the coil, simply as a means of facilitating tracing of the circuits.

20 Tap T1 leads to the shell of desuperheater D1 and thence to the shell of saturated steam heater S1 (the last in the series of such heaters). For the next tap the path is T2 to shell of D2 to shell of S2 and for the third tap the path is T3 to shell of D3 to shell of S3. T4 is connected directly to the shell of S4.

25 The three coils W1, W2 and W3 of desuperheaters D1, D2, D3 are connected in parallel between portions F1 and F2 of the boiler feed line.

The feed pump 11 delivers through the coils H4, H3, H2, H1 of the saturated steam heaters S4, S3, S2, S1 the flow being in series and in the order just stated to feed line F1.

30 The connections C1, C2, C3, C4 return the drip to the condenser hot well.

35 Fig. 2 is absolutely the same as Fig. 1 except that coils W3, W2, W1 of the desuperheater are connected in series between F1 and F2.

In the embodiments of Figs. 1 and 2 the superheated steam supplied by taps T1, T2 and T3 is desuperheated in D1, D2 and D3 by heat exchange with feed water after the latter has passed through all the saturated steam heaters S4, S3, S2 and S1.

40 45 In Fig. 2 in which the feed water connections are in series T1 which furnishes the hottest steam feeds D1 which is the last desuperheater in the water path, T2 feeds D2 which is next to last and so on. The same logic applies to the order of connections from the desuperheaters to the saturated steam heaters.

50 Thus the recovery of heat in the main desuperheating operations is effective to impart the highest practicable temperature to the feed water, and a better total heat transfer results.

55 Sometimes it is impracticable to remove the

entire superheat in one step. Where this is the case the arrangement shown in Fig. 3 may be adopted. Here the desuperheaters which effect the principal recovery of superheat are connected according to the invention. For illustrative purposes the multiple connection of Fig. 1 is chosen.

In Fig. 3 the parts identified by numbers 5 to 11 are the same as before and hence these numerals are used. Parts which correspond to lettered parts in Fig. 1 are identified by lower case letters.

As will be apparent the path t_1 , d_1 , s_1 is the same as in Fig. 1.

From t_2 the path is to d_2 thence to the shell of the secondary desuperheater d_4 and thence to s_2 .

From t_3 the path is to d_3 thence to the shell of secondary desuperheater d_5 thence to shell of tertiary desuperheater d_6 and thence to saturated steam heater s_3 .

The water path from pump 11 is via h_4 , h_3 , w_6 , h_2 , thence via w_4 and w_5 in parallel, to h_1 and then by f_1 through w_1 , w_2 and w_3 in parallel to f_2 and generator 5.

Despite the fact that the secondary and tertiary desuperheaters d_4 , d_5 and d_6 are intercollected between saturated steam heaters in the water path, the invention is present because the main desuperheaters are connected according to the invention and afford its advantages.

In Fig. 3 a pump 12 is used to deliver drip to the feed water line as shown.

I claim:

1. In a regenerative steam power plant of the type in which superheated steam from a generator is expanded through an extraction turbine, means for heating the feed water, comprising in combination a plurality of desuperheaters, each having a water path and a steam path; a plurality of saturated steam heat exchangers, each having a steam path and a water path; a plurality of connecting means from respective extraction stages of said turbine affording steam paths, each including the steam path of a desuperheater and the steam path of a heat exchanger connected in series; and means connecting the water paths of said desuperheaters and said heat exchangers in such order that the feed water passes through said desuperheaters after passing through said heat exchangers.

2. The combination defined in claim 1 in which the water paths of the desuperheaters are connected in parallel.

3. The combination defined in claim 1 in which

the water paths of the desuperheaters are connected in series.

4. The combination defined in claim 1 in which the water paths of the desuperheaters are connected in series and the desuperheaters are arranged in the direction of feed water flow in the order of ascending steam temperatures.

5. The combination of a regenerative steam power plant of the type in which steam from a generator is expanded through a turbine and steam is tapped off from a plurality of turbine stages; saturated steam heaters each having a steam path and a water path; a steam flow connection between each of said saturated steam paths and a corresponding turbine tap; primary desuperheaters each having a steam path and a water path, the steam path of each of said primary desuperheaters being interposed in the steam flow connection between one of the taps and the corresponding saturated steam heater; at least one secondary desuperheater having a steam path and a water path, the steam path of said secondary desuperheater being interposed in the steam flow connection between one of said primary desuperheaters and the corresponding saturated steam heater; a feed water path including the water paths of the saturated steam heaters in serial arrangement, the water path of said secondary desuperheater being interposed in said feed water path between the water path of the corresponding saturated steam heater and the water path of another saturated steam heater in said series, the feed water path passing ultimately through said primary desuperheaters; and connections for supplying condensate from the saturated steam heaters to the feed water path.
